COMBUSTION CONTROL

John J. Klinker, Decatur, Ill., assignor to A. W. Cash Company, Decatur, Ill., a corporation of Delaware

Application September 13, 1941, Serial No. 410,788

4 Claims. (Cl. 236—14)

This invention relates to combustion control, and more particularly to the control of combustion in a furnace having a forced draft air supply which is started and stopped in accordance with the demand for heat.

In furnaces of this type it is usual to start and stop the fuel supply at the same time as the air supply. The rate of fuel delivery during each operating period is ordinarily predetermined, but the rate of air flow usually varies with the resistance of the fuel bed. If the fuel bed is slightly thin the air flow will be increased, thereby increasing the rate of combustion and causing the fuel bed to become even thinner. Consequently it is not possible to burn the fuel efficiently. This difficulty becomes particularly serious when the demand for heat is low and the shut-down periods are prolonged. During such periods combustion continues at an appreciable rate because of air which passes through the forced draft fan by natural draft, and the fuel bed therefore becomes badly depleted.

It is accordingly one object of the invention to provide a comparatively simple and efficient apparatus for controlling combustion in a forced draft furnace of the start and stop type.

It is a further object of the invention to provide a simple and dependable apparatus for maintaining a predetermined rate of air flow in a forced draft furnace during the operating periods and for preventing substantially all air flow during the shut-down periods.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts, the single figure is a diagrammatic elevation, partly in section, of a forced draft furnace and associated combustion control apparatus.

The embodiment illustrated comprises walls 10 forming a furnace combustion chamber 11 fired by means of an underfeed stoker 12 having a retort 13 and tuyère blocks 15. Air is supplied to the space 16 beneath the retort by means of a forced draft fan 18 driven by a motor 19. The motor illustrated is an electric motor directly connected to the fan, and it also serves to actuate the stoker 12 through a chain-and-sprocket drive 20. The heat from the furnace 11 is utilized to generate steam in a boiler 22 mounted thereabove. The furnace gases flow in contact with

the boiler heating surfaces and then escape through a gas outlet or uptake 23 to a suitable stack (not shown). The gas outlet 23 is provided with an adjustable damper 24 having an operating arm 25.

The damper 24 is controlled automatically by a suitable regulator responsive to variations in the pressure in the furnace 11. For this purpose I preferably utilize an automatic regulator 27 of the type disclosed in the patent to Temple No. 1,992,048 granted February 19, 1935. This regulator comprises a pilot valve mechanism 28 supplied with a suitable fluid under pressure through a pipe 29 and connected by tubes 31 to a hydraulic motor 32. This motor 32 is connected to the damper operating arm 25 by means of a rod 33. The regulator 27 is connected to the furnace 11 by means of a pipe 34, so that the furnace pressure is effective to actuate the regulator. The regulator is adjusted to maintain a furnace pressure slightly below atmospheric pressure, say a negative pressure of one-tenth inch water column.

The electric motor 19 is connected to a suitable electrical supply 36 by means of conductors 37 which lead through an electro-magnetically actuated switch 38. This switch is provided with a holding coil 39, and the parts are so arranged that upon energization of this coil the switch will be closed and the motor 19 will start.

In order to control the rate of steam generation automatically, means is provided for starting and stopping the motor 19 at intervals in accordance with the demand for steam. For this purpose I have shown a pressure-actuated master switch 41 of the well-known mercury tube type connected by a pipe 42 to the steam delivery pipe 43 of the boiler 22, and arranged to close at a predetermined minimum steam pressure and open at a predetermined maximum steam pressure. This switch 41 is connected in series with the coil 39 across two of the leads from the power supply 36, so that the master switch will control the operation of the switch 38. Obviously, a power source independent of the supply 36 could be utilized for control purposes if desired.

In order to control the rate of air flow to the furnace, a forced draft damper 45 is shown mounted in the duct 46 between the fan 18 and the space 16 beneath the retort. This damper is provided with an operating arm 47 which is connected by a rod 49 to a hydraulic motor 50. This motor is controlled by a regulator 52 of the same type as the regulator 27 and comprising a pilot valve mechanism 53 supplied with a suitable fluid under pressure through a pipe 54 and

connected by a pair of conduits 55 to a four-way reversing valve 56, the latter being connected to the motor 50 by a pair of conduits 57. The regulator 52 is subjected to a pressure differential which is a function of the rate of air flow to the furnace, and for this purpose I may utilize the pressure differential across the boiler gas passages. As shown, one side of the regulator is subjected to the pressure in the furnace 11 through a pipe 58 connected to the pipe 34, and the other side of the regulator is subjected to the pressure in the gas outlet duct 23 anterior to the damper 24 through a pipe 59. With this construction, and the conduits 55 properly connected to the conduits 57, the regulator 52 will control the forced draft damper 45 in such a way as to maintain a predetermined air flow to the furnace regardless of changes in the resistance of the stoker fuel bed.

The four-way valve 56 is so constructed that the connections between the conduits 55 and 57 may be reversed when the stoker and fan are shut down, thus causing the motor 50 to close the forced draft damper and stop substantially all air flow to the furnace. For this purpose the valve is provided with four aligned ports 60, 61, 62 and 63, and with a reciprocable valve member 65 having two aligned valve disks 66 and 67 thereon. The disk 66 is located between the ports 60 and 61, whereas the disk 67 is located between the ports 62 and 63. The valve member 65 is actuated by a solenoid 68 which is connected across two of the conductors 37 between the stoker motor 19 and the switch 38. The arrangement is such that when the stoker is shut down the solenoid 68 will be deenergized, and the disks 66 and 67 will close the ports 61 and 63 as shown, the ports 60 and 62 being open. This will connect the conduits 55 to the conduits 57 in such a way as to cause the motor 50 to close the forced draft damper 45. When the stoker is operating, the solenoid 68 will be energized, and the valve member will be raised to close the ports 60 and 62, thus reversing the connections between the conduits 55 and 57, and causing the regulator 52 to control the forced draft damper 45 to maintain a predetermined rate of air flow.

The operation of the invention will now be apparent from the above disclosure. Assuming that the steam pressure is sufficiently high, the various parts will be positioned as illustrated. The master switch 41 will be open, the coil 39 will be deenergized, the switch 38 will be open, and the stoker motor 19 will be shut down. The regulator 27 will hold the damper 24 nearly closed, maintaining a slight predetermined draft in the furnace 11. The solenoid 68 will be deenergized and the valve 56 will connect the conduits 55 and 57 in such a manner that the motor 50 will close the forced draft damper 45, the regulator 52 being subjected to a lower pressure differential than that for which it is adjusted. Thus the damper 45 will be closed during the shut down period so that substantially no air can enter the furnace 11. If now the steam pressure drops sufficiently to close the master switch 41, the coil 39 will be energized, the switch 38 will close and the motor 19 will start the fan 18 and stoker 12. The solenoid 68 will be energized, reversing the valve 56 and causing the regulator 52 to control the forced draft damper in accordance with the pressure differential across the gas passages of the boiler 22, as transmitted through the pipes 58 and 59. Since the regulators 27 and 52 are of the same type, the forced draft damper 45 will not

open any faster than the uptake damper 24 will be opened to accommodate the increasing gas flow, so that no objectionable flare-backs will occur during the starting of the fan. The forced draft damper 45 will be automatically controlled by the regulator 52 to provide a predetermined rate of air flow during each operating period, making it possible to maintain a desired fuel-air ratio despite changes in fuel bed resistance. As combustion continues and the steam pressure rises sufficiently to open the master switch 41, the coil 39 will be deenergized, the switch 38 will open, the motor 19 will stop, and the parts will be restored to the positions shown in the drawing until the start of the next operating cycle.

It will be understood that many changes and variations may be made in the construction and arrangement of the various parts without departing from the spirit of the invention, and therefore it is intended to include all such changes and variations within the scope of the following claims.

Having thus described my invention, what I claim as new and desire to secure by Letters Patent is:

1. A control system for a furnace having fuel supply means, a fan to supply forced draft air and a forced draft damper comprising means to start and stop the fuel supply means and the fan in accordance with the demand for heat, a motor to actuate the damper, a regulator responsive to the rate of air flow and having a pilot mechanism, connecting means from the pilot mechanism to the motor so arranged that upon a decrease in the rate of air flow the motor will move the damper toward open position and vice versa, and means effective when the fan is stopped to reverse the said connecting means so that upon a decrease in the rate of air flow the motor will move the damper toward closed position, thereby closing the damper when the fan is stopped.
2. A control system for a furnace having a passage for the flow of heating gases, fuel supply means, a fan to supply forced draft air and a forced draft damper comprising means to start and stop the fuel supply means and the fan in accordance with the demand for heat, a motor to actuate the damper, a regulator responsive to the pressure drop in the passage and having a pilot mechanism, connecting means from the pilot mechanism to the motor so arranged that upon a decrease in the said pressure drop the motor will move the damper toward open position and vice versa, and means effective when the fan is stopped to reverse the said connecting means so that upon a decrease in the said pressure drop the motor will move the damper toward closed position, thereby closing the damper when the fan is stopped.
3. A control system for a furnace having fuel supply means, a fan to supply forced draft air and a forced draft damper comprising means to start and stop the fuel supply means and the fan in accordance with the demand for heat, a hydraulic motor to actuate the damper, a regulator responsive to the rate of air flow and having a pilot valve, connecting means for the flow of pressure fluid between the pilot valve and the motor so arranged that upon a decrease in the rate of air flow the motor will move the damper toward open position and vice versa, the said connecting means including a reversing valve, and means effective when the fan is stopped to actuate the said reversing valve so that upon a

decrease in the rate of air flow the motor will move the damper toward closed position, thereby closing the damper when the fan is stopped.

4. A control system for a furnace having fuel supply means, a fan to supply forced draft air and a forced draft damper comprising means to start and stop the fuel supply means and the fan in accordance with the demand for heat, a double-acting hydraulic motor to actuate the damper, a regulator responsive to the rate of air flow and having a pilot valve two conduits for the flow of pressure fluid in opposite directions

between the pilot valve and the motor so arranged that upon a decrease in the rate of air flow the motor will move the damper toward open position and vice versa, a reversing valve connected to the said conduits, and means effective when the fan is stopped to actuate the said reversing valve so that upon a decrease in the rate of air flow the motor will move the damper toward closed position; thereby closing the damper when the fan is stopped.

JOHN J. KLINKER.
